Specification for Design.

Patented July 8, 1913.

Application filed March 25, 1913. Serial No. 756,795. Term of patent 14 years.

To all whom it may concern:

Be it known that I, CHARLES W. COFFIN, a citizen of the United States, residing at Portland, in the county of Cumberland and State of Maine, have invented a new, original, and ornamental Design for Tables, of which the following is a specification, reference being had to the accompanying drawings, forming part hereof.

In the drawings: Figure 1 is a top plan view, and, Fig. 2 is a side elevation.

I claim:

The ornamental design for a table, as shown.

In testimony whereof I affix my signature in the presence of two witnesses.

CHARLES W. COFFIN.
